UNITED STATES PATENT OFFICE.

WILLIAM R. GORRELL, OF ALHAMBRA, CALIFORNIA, ASSIGNOR OF ONE-HALF TO
HENRY BARKSCHAT, OF LOS ANGELES, CALIFORNIA.

COLLAPSIBLE INCINERATOR.

Application filed February 24, 1925. Serial No. 11,095.

This invention has to do generally with incinerators for burning rubbish and the like.

In spite of the great demand for household incinerators in many localities, they are not stocked by most dealers due to the excessive space they occupy both in storage and during transportation, due to their bulk and hollow nature.

It is, therefore, an object of my invention to provide an incinerator which may be collapsed into a package of comparatively small compass for transportation and storage, and yet be easily and quickly erected by the purchaser without the aid of tools or skilled labor.

I have also provided certain novel features of construction which will be explained in detail in the following specification, reference being made to the accompanying drawings, wherein:

Fig. 1 is a side elevation of an incinerator made in accordance with my invention;

Fig. 2 is a front elevation of the incinerator;

Fig. 3 is a plan view of Fig. 2;

Fig. 4 is a perspective view of the incinerator collapsed;

Fig. 5 is an enlarged horizontal section showing the preferred corner construction of the incinerator;

Fig. 6 is an enlarged section on line 6—6 of Fig. 1 showing the hinge connection of the side panels;

Fig. 7 is a section on line 7—7 of Fig. 6;

Fig. 8 is an enlarged section on line 8—8 of Fig. 2 but showing the draft door hooked in raised position;

Fig. 9 is a fragmentary section on line 9—9 of Fig. 3; and

Fig. 10 is a fragmentary side elevation of Fig. 9 as viewed from the right thereof.

In the drawings, the various elements of the incinerator are so proportioned and relatively arranged that the erected structure is in the nature of a square base, truncated pyramid, but it will be understood it lies within the scope of my invention to so vary the proportions of the elements that the incinerator may be of any desired shape possible to the combinations set up in certain of the appended claims. While I will describe the structure as made up of corrugated sheet metal plates, it will be understood it lies within the scope of the invention, in its

broader aspects, to use other material for the purpose.

Front and rear panels 10 and 11, respectively, are preferably made up of corrugated sheet metal and are hingedly connected at 60 their side edges to side panels 12, each of the latter being made up of corrugated sections 13 and 14 which are hingedly connected along their vertically extending edges. In the illustrated incinerator, each side section 65 is substantially one-half the width of the front or rear panel, but it will be understood this proportion is not controlling.

I have devised a hinge connection which is especially suited to the purpose, due to the 70 simplicity and cheapness of its construction, ease of attachment, and effectiveness in operation.

Referring particularly to Figs. 6 and 7, it will be noted that the two members 15 and 16 75 making up each hinge, are formed of wires bent upon themselves to form a shank 17, these shanks being thrust through aligned holes 18 in the opposite sides of corrugation swells 19. The holes may be conveniently 80 punched before the corrugations 19 are formed. The free ends 20 of the wires are spread transversely of the shank portions to prevent longitudinal displacement of the members in a given direction, while eyes 21 85 and 22 at the other ends of the shanks are interengaged to form a hinge connection between sections 13 and 14. Eye 21 is formed by spreading the shank wires of member 15, while the doubled over shank end of member 16 is passed through eye 21 and bent to 90 form eye 22. The edges 23 of sections 13 and 14 overlap as clearly shown in Fig. 7 and form a sufficiently tight joint. It will be noted this joint so coacts with the hinge connection 95

that the sections are held against outward movement at their junction when the incinerator is fully opened up, and yet the sections may be folded with outer face against outer face when it is desired to 100 collapse the incinerator (see Fig. 4). In order to prevent accidental folding of the sections, I may provide a pivotally mounted button or bar 23^a (Fig. 1) on one of the sections, said bar being adapted to be swung 105 transversely across the section joint and into engagement with keepers 24 when the incinerator is erected.

The corner hinges 25 which connect the front and rear panels to the side panels 110

are constructed similarly to those just described, except that shanks 26 extend through inwardly projecting corrugation swells 27, and the two shanks of a given hinge extend at right angles to one another when the incinerator is erected. One edge 28 of either full panel or side section is angularly bent so it overlaps the adjoining edge 29 of the adjacent panel or section to provide a sufficiently tight joint and, with the hinges, to limit the spreading of the adjacent panels beyond a predetermined extent. However, this overlap does not interfere with inward collapsing movement of the adjacent panels to the position of Fig. 4.

Cover 30 is made up of screening 31, preferably having a metal binding strip 32 thereabout. The upper edge of the rear panel 11 is turned over at 33 to support a cross rod 34 which serves as a pintle or hinge pin for cover 30. Rods 35 serve as reinforcement for screen 31 and to attach the cover hingedly to rod 34. The forward end of the rods preferably hook through the screen at 36, while their opposite ends 37 are bent more or less loosely around bar 34. The rods may be wired or otherwise suitably secured to the screen at 35^a. It is self-evident that this hinge connection between rear panel and cover permits the cover to be raised for the insertion of rubbish when the incinerator is erected, or to be turned clear over into the position of Fig. 4 when the incinerator is to be collapsed.

Front panel 10 has a draft opening 38 over which is hung door 39, member 40 serving both as reinforcement for the door and as a hinge connection between panel and door. Member 40 is a rod bent into substantially U-shape, the loop end 41 passing through door slot 42 and being bent under the inner face of the door as clearly shown in Fig. 8. The legs 43 of member 40 are further spread at 44 and pass through holes 45, provided in the angular extension 46 of the door, and thence pass through holes 47 in panel 10. The leg ends 48 are then bent behind the inner face of the panel to prevent door displacement, but they permit the door to be swung open or shut.

The shank 49 of hook 50 extends through panel aperture 51, transverse extensions 52 being disposed against the inner face of the panel to hingedly connect the hook to the panel. When it is desired to hold door 39 in open position, hook 50 is engaged with door extension 46, as clearly illustrated in Fig. 8. When the door is closed, hook 50 hangs down in a position adjacent the front panel.

It will be seen I have provided a strong, durable incinerator which may be folded so as to occupy a minimum of space or may be fully erected without the aid of tools.

65 The various hinge connections are such that

none of their elements are joined by rivets or the like, lending greatly to the easy and cheap fabrication of the device, without in any way impairing its efficiency or useful life.

70 It is to be understood, I wish the drawings and description to be considered merely as illustrative of and not restrictive on the broader claims appended hereto, for various changes in design, structure and arrangement may be made without departing from the spirit and scope of said claims.

Having described a preferred form of my invention, I claim:

1. A collapsible incinerator embodying a 80 plurality of hingedly connected panels, certain of said panels each comprising a plurality of substantially co-extensive adjacent sections, hinges connecting said adjacent sections near their adjoining edges in a manner whereby the sections of a given panel are foldable one upon the other when the incinerator is collapsed, the adjoining edges of adjacent sections overlapping and being adapted to engage one another when the 90 incinerator is erected and thereby limiting folding movement of the sections in one direction.

2. A collapsible incinerator embodying a 95 plurality of hingedly connected panels, certain of said panels each comprising a plurality of substantially co-extensive adjacent sections, hinges connecting said adjacent sections near their adjoining edges in a manner whereby the sections of a given panel 100 are foldable one upon the other when the incinerator is collapsed, the adjoining edges of adjacent sections overlapping and being adapted to engage one another when the incinerator is erected and thereby limiting 105 folding movement of the sections in one direction, and releasable means on the sections adapted to hold them from folding movement in the other direction.

3. In a collapsible incinerator embodying 110 a plurality of panels, hinges connecting adjacent panels and each embodying a pair of shanks, one to each panel, each shank being formed by bending a wire upon itself, said shanks extending transversely through 115 protuberances on the panel faces, the free ends of the shank wires being spread in a manner to engage one side of the corresponding protuberance, an eye formed at the other end of one shank by spreading the shank wires apart, and an eye formed on the other shank by bending the loop end of the shank wires through the first mentioned eye.

4. In a collapsible incinerator embodying 125 a plurality of hingedly connected wall panels, a cover comprising a screen, and a hinge connection between the cover and one of the panels, said connection embodying a rod secured to said one panel and extending 130

along the top thereof, and a pair of bars extending over the screen and secured thereto, said bars having eyes adapted to engage the panel carried rod loosely.

5. In a collapsible incinerator embodying a plurality of hingedly joined panels, a closure for a draft opening provided in one of the panels, said closure comprising a sheet metal door having an outwardly extending angular extension near the upper edge thereof, and means for hinging the door to the panel, said means comprising a substantially U shaped member having its loop end connected to the door, the legs of 10 the member extending through said angular extension and said panel, and the free ends of the legs being turned transversely in a manner to engage the inner face of the panel.
- 15 6. In a collapsible incinerator embodying a plurality of hingedly joined panels, a closure for a draft opening provided in one of the panels, said closure comprising a

sheet metal door hinged to the panel, an outwardly extending angular extension on 25 the door near its upper edge; and a hook movably mounted on the panel and adapted to be moved into engagement with said extension for releasably holding the door in open position.

30 7. A collapsible incinerator embodying a plurality of panels adapted to extend angularly with respect to one another when the incinerator is erected, hinges connecting adjacent panels near their adjoining edges 35 whereby said panels are foldable one upon the other when the incinerator is collapsed, a given edge of each panel being bent angularly to overlap the adjoining edge of the adjacent panel when the incinerator is 40 erected and thereby limiting the folding movement of the panels in one direction.

In witness that I claim the foregoing I have hereunto subscribed my name this 4th day of February, 1925.

WILLIAM R. GORRELL.
